UNITED STATES PATENT OFFICE

EUGENE H. SALMON, OF COLUMBIA, SOUTH CAROLINA

SPECIAL TYPE

Application filed May 19, 1930. Serial No. 453,786.

This invention relates to special type for printing or for making impressions.

The primary objects of the present invention are to provide a type unit constructed for use in a make-up frame with other type matter and of being subjected to pressures, suction and other conditions obtaining in usual printing operations, such as found, for instance, in the use of large stereotype presses, said type unit having two major selectively related groups of printing or impression faces or characters, letters, numbers, symbols, hands, pointers or other elements, one group of characters being annularly disposed and the other group being disposed radially about the axis of, and encircled by, said annular group; to provide such a type unit wherein one or more of the hands or pointers of the radially disposed group may be changed in radial position with relation to each other and to the numbers, letters or symbols of the annularly disposed group; and to provide such a unit wherein one or more of said hands or pointers of said radially disposed group may be entirely displaced, its place either being left blank or being occupied by a substitute radially extending hand, pointer or symbol. More narrowly considered, important objects are to provide a type unit such as above referred to and comprised of a plurality of separate but interrelated type elements; to provide a type unit such as above described comprised of a main frame carrying the annularly disposed series of characters, letters, numbers or symbols and having a central opening in association with a plurality of separate type elements disposed in said opening and adapted to cooperate with the wall of said opening; and to provide a type unit such as above described and comprising a plurality of radially disposed segments having abutting radial faces, in combination with a divided frame having a central opening defined by an annular wall serving to engage the radially outer ends of said segments to squeeze all of said segments radially inward into tight contact.

Obviously, such a type unit may be used not only for actual printing operations, but

also as a master pattern or die from which to take impressions to form therein rubber stamps or metal stamps or printing mats.

In this application I show and describe only several of the more preferred embodiments of my invention simply by way of illustration of the practice thereof, as by law required. However, I realize that my invention is capable of many other and different embodiments and that the various details thereof may be modified in a number of different ways, all without departing from my said invention broadly considered. Therefore, the drawings and description herein are to be considered as merely illustrative and not as exclusive.

Primarily the invention is intended for use in printing a clock face in the midst of other printed matter, as, for instance, a store advertisement of a special sale, indicating the time when the sale starts by the positions of the clock hands. However, while primarily intended to print a clock face, the invention is not limited thereto and may be employed in a great many different ways, the annularly disposed and, if necessary, the radially disposed group or groups of symbols illustrated being substituted by others suitable to the intended use.

In the accompanying drawings:

Figure 1 represents a front elevation of a type unit embodying my invention as set up in the center of other type matter, the set-up type or composition of type being locked up as usual in a conventionally indicated printer's chase.

Figure 2, a front elevation of said type unit by itself in set-up position, the hands being in one selected position;

Figure 3, a sectional view on the line 3—3 of Fig. 2, looking in the direction of the arrows, and extending through some adjacent type matter B, such as illustrated in Fig. 1;

Figure 4, a front elevation of the minute hand segment, which may have its radially inner end rounded with its front face in the printing plane to simulate the hands' shaft and hubs, as illustrated;

Figure 5, a view similar to Fig. 4 of the hour hand segment;

Figure 6, a view similar to Fig. 4 whereon the minute and hour hands are superposed and aligned to represent twelve o'clock;

5 Figure 7, a perspective view of the segment illustrated in Fig. 4;

Figure 8, a perspective view of the segment illustrated in Figure 5;

Figure 9, a front elevation of a blank segment;

10 Figure 10, a front elevation of a slight modification; and

Figure 11, a front elevation of a further slight modification.

Referring now in detail to the drawings, 15 A designates a conventional printer's chase; B, usual set-up type matter about the special type unit of this invention; C, the usual rules or furniture applied against the adjacent outer edge faces of the composition of type, 20 and D the usual printer's clamps, conventionally illustrated, for locking up the type composition in the chase A in accordance with usual practice.

25 The special type unit of the specific embodiment illustrated in the first nine views of the drawings consists of sixteen individual specially formed pieces of type, being the two divided frame members 1 and 1^a making joint with each other, as at 8, preferably on a 30 straight light disposed to one side of, but close to, the center line of the unit as a whole, and preferably being so located as not to intersect any of the numerals or characters 2 or minute points 3 of the two concentric raised 35 annular series of numbers, marks or symbols 2 and 3 preferably formed integrally with said frame members 1 and 1^a, eleven segments 4 and one each of segments 5, 6 and 7.

40 Said members 1 and 1^a have their opposed faces preferably extending parallel to their common axis and formed to together define a central circular opening concentric with the two concentric radially successively disposed series of symbols 2 and 3 to receive in said 45 opening a total of twelve of the segments 4, 5 and 6 or 4 and 7 when the adjacent end portions are in, or substantially in, contact, as at 8, and when said segments are pressed radially inward by said frame members 1 50 and 1^a to be in tight binding contact with the radial faces 9 of the next adjacent segments and by their radially inner arcuate faces 10 in, or substantially in, contact with the opposed correspondingly formed face portion 55 of the rounded or cylindrical extension 11 of segment 5 or segment 7, as the case may be.

The segment 5 will preferably be formed with a raised circular printing surface 12 preferably extending over the entire circular 60 area of the rounded or cylindrical extension 11 of segment 5, and with a radially disposed raised printing surface 13 disposed centrally of the printing face of said segment 5 and representing the minute hand of a clock.

65 The segment 6 will be provided with a ra-

dially disposed preferably integral raised printing surface 14 extending centrally of the printing surface of said block 1 and representing the hour hand of the clock.

70 The segment 7 will have a similar radially preferably centrally disposed raised printing face 15 formed to simulate the two clock hands when superposed, as at 12 o'clock, said face 15 preferably being very finely grooved along the sides of the minute hand across the hour hand to give a hair line break between the two in the resulting print.

75 The frame elements 1 and 1^a may, and preferably will, be formed with a narrow annular raised printing surface 16 concentric with and immediately outside of the annular series of minute points 3, and with a similar annular printing face 17 disposed between the annular series of numerals or characters 2 to more perfectly represent a clock face.

80 The segments 4 will have no raised printing surface, but merely function as fillers.

85 The segments 4, 5, 6 and 7 and the frame members 1 and 1^a are made of the same standard thickness of standard present-day metal type matter, with the symbols, characters, 90 hands, bands or the like 2, 3, 12, 13, 14, 15, 16 and 17 raised to the standard height of approximately one thirty-second of an inch above the surface of the respective frame elements 1 and 1^a and segments 5, 6 and 7 and rounded or cylindrical extension 11 of segment 5, so that said special type unit may be set up and used in the midst of, and as a part of, a composition of type, as illustrated in 95 Figs. 1 and 3.

100 Preferably the unit as set up will not be more than one and a half to two inches square, preferably less, so that when made on that scale its length or width will be approximately only one and a half to twice its thickness. However, it may, of course, be made in larger sizes with the same thickness and for the sake of clarity I have illustrated herein in 105 Figs. 2 to 10, inclusive, a size approximately five and a half times as wide as it is thick: that is to say, roughly, five inches wide by slightly over nine-tenths of an inch thick, whereas in the smaller size mentioned it will be of the same thickness, but only 110 four-elevenths as wide, as illustrated.

115 Primarily this special type unit is intended for use in connection with newspaper advertisements of special sales for a limited time or to start at a special hour, the purpose being 120 to particularly emphasize the hour when the sale starts. Fig. 1 illustrating a composition of type wherein the special type unit is so employed.

125 In use, assuming that the sale starts at nine o'clock and the special type unit is to be set to print this time, the segment 5 would be set with its minute hand 13 pointing at 12 and the segment 6 would be set with its hour hand 14 pointing at 9 and with its inner end 130

10 abutting the cylindrical portion 11 of segment 5 and the stem of hour hand 14 fitting closely against the hub or printing face 12, and ten filler segments 4 would be inserted 5 on both sides of and between the segments 5 and 6.

Were the starting hour to be twelve o'clock, the segments 5 and 6 would be taken out, the segment 7 with its superposed hands 15 pointing at 12 would be substituted and eleven filler segments 4 would be employed.

In case the sale were to start at five minutes after nine the segment 5 with its minute hand 13 would be arranged to point slightly beyond one and the segment 6 with its hour hand 14 to point slightly beyond nine, and so on, according to the actual time of the start of the sale or other time desired to be printed.

Of course, if desired, in order to obtain a finer or more exact setting of the hands for five minutes or less intervals twice or three times or four times the number of correspondingly smaller segments of the same 25 radial length and thickness may be used, or two sizes of filler segments might be used, as is usual practice in the printing art; for instance, or or two of the segments 4 might be radially divided into four or more segments 30 4^a, as shown in the modification illustrated in Fig. 11.

In the slight modification illustrated in Fig. 10 the rounded or cylindrical central part 11 is formed as a cylindrical center element 11^a separate from the segment 5 or segment 7, as the case may be. Otherwise the construction and operation are the same as in the preferred form.

While I have shown and described a major specific embodiment of the preferred form of my invention, together with several minor modifications thereof, considering my invention in its broader aspects it is not essential that the frame shall be comprised of two separate members, such as 1 and 1^a, and shall not be integral, nor that there be segments such as 4, 5, 6 and 7, nor that the radially disposed hands or symbols 13, 14 and 16 shall be integral with, or carried by, such 50 thick segments 5, 6 and 7 respectively, it sufficing if the special type unit comprise a structure such as to suit it for incorporation substantially anywhere in the body of a type composition and have two or more relatively 55 selectively disposed groups of printing surfaces, one group being disposed radially and the other group or groups being disposed concentrically about said radial group, there being provision for adjusting the one group 60 with relation to the other whereby said radial group may selectively point at any one or any two or more of the symbols of the 65 concentrically disposed group or groups of symbols.

I claim:

1. A special type unit consisting of a frame 70 consisting of a plurality of members having opposed faces adapted to abut and being cut out between said abutting surfaces in arcs to together define between them, when their opposed faces are in abutment, an opening, and one of said members having a series of printing surfaces formed on its lower face adjacent to its said arcuate face, in combination with a plurality of interchangeable segmental blocks having radially outer end faces and straight radial faces, some of said segmental blocks being provided on their respective lower faces with printing 75 surfaces extending radially outward, said plurality of segmental blocks being adapted to be disposed in said opening to fill the same, and the said opposed arcuate faces of said members being adapted to engage the opposed radially outer end faces of said segmental blocks to force said blocks radially inward into tight squeezing contact with each other, the said frame members and segmental blocks all being of the same thickness. 80

2. A special type unit consisting of a frame 90 consisting of a plurality of members having opposed faces cut out to together define between them an opening, and said members having together a composite circular series 95 of printing surfaces formed on their lower faces, in combination with a plurality of interchangeable blocks having outer end faces adapted to be engaged by said frame members, and side faces adapted to engage the opposed side faces of the next adjacent blocks, one of said segmental blocks being provided on its lower face with a printing 100 surface extending endwise thereof, said plurality of blocks being adapted to be disposed in said opening to fill the same, and the opposed faces of said frame members being adapted to engage the opposed outer end faces of said blocks to force said blocks inward into tight squeezing contact with each other. 105

3. A special type unit consisting of a frame 110 consisting of a plurality of members having opposed faces cut out to together define between them an opening, and said members having together a composite series of printing surfaces formed on their lower faces, in combination with a plurality of blocks adapted to be disposed in said circular opening to 115 fill the same, and the said opposed faces of said frame members being adapted to engage said blocks to force said blocks inward into tight, squeezing contact with each other, one of said blocks being provided on its lower face with an endwise extending printing surface. 120

4. A special type unit consisting of a frame 125 formed with an opening and having on its lower face a series of printing surfaces about 130

said opening, in combination with a plurality of blocks adapted to be disposed in said opening to fill the same, and as operatively disposed therein making tight frictional contact therewith and with each other, several of said blocks being provided on their lower faces with printing surfaces extending endwise thereof.

- 5 5. A special type unit adapted for use as part of a type composition as locked up in the usual printer's chase, said unit as set up having a smooth rear face lying in the same plane as the rest of the rear face of such composition and having impression faces all lying in the same plane as the impression faces of the rest of such composition, said unit being formed with a plurality of selectively related series of impression surfaces, one of said series being disposed concentrically about the axis of, and embracing, the other series, and said latter series of impression surfaces extending radially from said axis toward at least one selected individual impression surface of said concentric series.
- 10 6. A special type unit adapted for use as part of a type composition as locked up in the usual printer's chase, said unit as set up having a smooth rear face lying in the same plane as the rest of the rear face of such composition and having impression faces all lying in the same plane as the impression faces of the rest of such composition, said unit being formed with a plurality of selectively related groups of impression surfaces, one of said groups being disposed about the other group, and said latter group comprising an impression surface extending at an angle to all of the individual impression surfaces of said former group.
- 15 7. A special type unit adapted for use as part of a type composition as locked up in the usual printer's chase, said unit as set up having a rear face lying in the same plane as the rest of the rear face of such composition and having impression faces all lying in the same plane as the impression faces of the rest of such composition, said unit being formed with a plurality of selectively related series of impression surfaces, one of said series being disposed about the other group, and said latter group of impression surfaces extending from a single point from said axis toward several selected individual impression surfaces of said concentric series.
- 20 8. In testimony whereof, I have signed my name to this specification at Columbia, South Carolina this 17th day of May, 1930.

EUGENE H. SALMON.
